UNITED STATES PATENT OFFICE.

THOMAS FLEMING, OF SOUTH ORANGE, NEW JERSEY.

METHOD OF AND TOY DEVICE FOR PROJECTING SHADOW PICTURES.

Application filed December 2, 1921. Serial No. 519,450.

To all whom it may concern:

Be it known that I, THOMAS FLEMING, a citizen of the United States and a resident of South Orange, in the county of Essex and State of New Jersey, have invented a new and Improved Method of and Toy Device for Projecting Shadow Pictures, of which the following is a full, clear, and exact description.

- 10 This invention relates to a method of and toy device for projecting shadow pictures. An object of the invention is the provision of a method whereby any desired material may be formed or treated in accordance therewith whereby the projection of shadow pictures thereby will result in pictures which very accurately and in a lifelike manner simulate the subject which it is desired to project.
- 20 Another object resides in the provision of a sheet of material so formed that the projection of a shadow picture therethrough, or by means of this device, will result in a much improved and more lifelike picture.
- 25 A further object resides in the particular construction and arrangement of parts which are hereinafter described and claimed and shown in the accompanying drawings.

The invention is illustrated in the drawing, which is a perspective view showing the device and the shadow picture which it forms when held up in front of a source of light.

The particular application of the invention shown is a design of the device of the general preferred type, although it is understood that modifications in the construction and arrangement of the parts and in the character of the materials used may be adopted without departing from the spirit of the invention.

In the drawing, the figure marked "A" is a sheet 1 of material, preferably cardboard, which has been cut to any desired outline so that when held up in front of a source of light a shadow of this outline will be projected on the desired surface. This sheet may, of course, be of any desired size and material and outline. Since it is, however, intended to project a picture and not a mere outline or silhouette it becomes necessary to treat the sheet so that a most accurate and lifelike picture will be projected. I have found, therefore, that by studying the subject which it is desired to project or throw on a surface as a shadow picture,

there are certain portions of this subject, which may be a photograph, a view of a person or other animate object, which are so illuminated by the light falling thereon as to produce what are known in the art as "lights", especially "high lights". In other words, if the entire surface of an object is subjected to the same degree of light and that same degree of light is reflected into the observer's eyes from all points of the object, then there is no contrast presented to the eyes of the observer from which a pictorial representation can be formed. However, when a picture contains these so-called lights, there is always a sufficient contrast for the observation of a definite picture or impression of the subject. I have found, also, that if the sheet of material 1 above mentioned has cut from within its outline those portions, such as 2, 3, 4, etc., of the picture or figure which in the real subject are high lights, when light is, therefore, transmitted through this sheet these portions of the sheet or the picture projected on any desired surface will be illuminated and form the high lights desired in the simulation of the original subject.

Therefore, in the representation of the invention as shown in the drawings I have shown a sheet cut out to represent the outline of a well-known actor, and from this sheet I have cut out portions thereof which are located in those parts of the sheet in which the high lights are located in the original picture of the subject or on the features of the subject itself when disposed in a certain position with respect to the light thrown thereon. I have found that by cutting out the high-light portions of an opaque sheet of material representing in outline a given figure, a very remarkable, accurate and lifelike simulation of the original subject is produced when this sheet is held up in front of a source of light and the shadow picture thrown on any surface.

The figure marked "B" of the drawing is a representation of the shadow picture formed by the projection of light against and through the sheet shown in Figure A. It will be observed not only by a consideration of this drawing but by cutting a sheet in accordance with the above-mentioned invention that astonishing likenesses are produced. It is apparent that these pictures may be formed by cutting out of a sheet of cardboard, paper or any other

opaque substance, the light portions of a portrait, caricature or animal, by means of a suitable die, knife or stamp in such manner that sunlight or artificial light will cast 5 a shadow representing the complete picture of the object intended.

What I claim is:

A device for projecting life-like silhouettes which comprises a sheet of material

having the desired outline of the silhouette 10 to project the same on a surface when the sheet is held between the surface and a source of light, said sheet having high-light portions of the silhouette being projected cut out so that the light will be projected 15 therethrough to render the projected silhouette life-like.

THOMAS FLEMING.
